UNITED STATES PATENT OFFICE.

WILLIAM A. SMETHURST, OF PHILADELPHIA, PENNSYLVANIA.

DESIGN FOR A GAME-BOARD.

SPECIFICATION forming part of Design No. 24,454, dated July 2, 1895.

Application filed May 2, 1895. Serial No. 547,937. Term of patent 3½ years.

To all whom it may concern:

Be it known that I, WILLIAM A. SMETHURST, a citizen of the United States, residing in the city and county of Philadelphia, State of Pennsylvania, have invented and produced a new and original Design for a Game-Board, of which the following is a specification, reference being had to the accompanying drawing, forming part thereof.

10 The leading feature of my design for a game-board is such board having thereon the representation of a many-pointed star with intersecting sides, disks on the points of the star, and a disk in the center thereof.

15 In the drawing, which represents a plan view of a game-board embodying my design, A designates the representation of a many-pointed star, which is formed of a series of

connected V-shaped figures B, whose sides intersect and are continuous one of the other. 20 At the angles or points of the star are representations of disks C. In the center of the figure is the representation of a disk D, from which radiates a line E, which joins one of the disks C. A line F extends from the apex 25 of one of the V-shaped figures B to one of the disks C, intermediate of the base of the legs of said figure B.

What I claim is—

The design for a game board, substantially 30 as described and shown.

WILLIAM A. SMETHURST.
